Primary Examiner — Selina Sikder*(74) Attorney, Agent, or Firm* — Holland & Hart(57) **CLAIM**

The ornamental design for a “touch panel,” as shown and described.

DESCRIPTION

FIG. 1 is a top perspective view of a touch panel according to the present invention;

FIG. 2 is a rear perspective view thereof;

FIG. 3 is a front view thereof;

FIG. 4 is a right side view thereof;

FIG. 5 is a left side view thereof;

FIG. 6 is a top view thereof;

FIG. 7 is a bottom view thereof;

FIG. 8 is a rear view thereof;

FIG. 9 is a top perspective view of an alternative embodiment of a touch panel design according to the present invention;

FIG. 10 is a rear perspective view of the alternative embodiment thereof;

FIG. 11 is a front perspective view of the alternative embodiment thereof;

FIG. 12 is a right side perspective view of the alternative embodiment thereof;

FIG. 13 is a left side perspective view of the alternative embodiment thereof;

FIG. 14 is a top view of the alternative embodiment thereof;

FIG. 15 is a bottom view of the alternative embodiment thereof;

and,

FIG. 16 is a rear view of the alternative embodiment thereof.

The broken line showing of the touch panel is for illustrative purposes only and forms no part of the claimed design.
